CLAIM

The ornamental design for a cooling manifold, as shown and described.

DESCRIPTION

FIG. 1 is an upper perspective view of a first design of a cooling manifold;
FIG. 2 is a front view of the design of FIG. 1;
FIG. 3 is a rear view of the design of FIG. 1;
FIG. 4 is a first side view of the design of FIG. 1;
FIG. 5 is a second side view of the design of FIG. 1;
FIG. 6 is a top view of the design of FIG. 1;
FIG. 7 is a bottom view of the design of FIG. 1;
FIG. 8 is a lower perspective view of the design of FIG. 1;
FIG. 9 is an upper perspective view of a second design of a cooling manifold;
FIG. 10 is a front view of the design of FIG. 9;
FIG. 11 is a rear view of the design of FIG. 9;
FIG. 12 is a first side view of the design of FIG. 9;
FIG. 13 is a second side view of the design of FIG. 9;
FIG. 14 is a top view of the design of FIG. 9;
FIG. 15 is a bottom view of the design of FIG. 9; and,
FIG. 16 is a lower perspective view of the design of FIG. 9. The broken lines shown in the drawings are included for the purpose of illustrating the unclaimed boundary and unclaimed portions of the cooling manifold. The broken lines form no part of the claimed design.

1 Claim, 16 Drawing Sheets
